R. W. SCOTT.
KNITTING MACHINE NEEDLE.
APPLICATION FILED OCT. 24, 1916.

1,248,020.

Patented Nov. 27, 1917.

UNITED STATES PATENT OFFICE.

ROBERT W. SCOTT, OF NEW YORK, N. Y., ASSIGNOR, BY MESNE ASSIGNMENTS, TO SCOTT & WILLIAMS, INCORPORATED, A CORPORATION OF MASSACHUSETTS.

KNITTING-MACHINE NEEDLE.

1,248,020.

Specification of Letters Patent. Patented Nov. 27, 1917.

Application filed October 24, 1916. Serial No. 127,317.

To all whom it may concern:

Be it known that I, ROBERT W. SCOTT, a citizen of the United States, and resident of New York city, in the county of New York and State of New York, have invented new and useful Improvements in Knitting-Machine Needles, of which the following is a specification.

My invention relates to that class of knitting machine needles having integral projecting butts to engage cams or other elements of the machine in which they are used, objects of my invention being to provide a needle accurate in dimensions from tip to butt, which can be made from wire by an improved and simplified series of bending, flattening, swaging, machining and other well-known operations, and which shall be better adapted than bent wire needles at present known to resist the wear and strain of use.

As wire knitting machine needles are at present constructed, the wire of which the stem or shank of the needle is composed is doubled upon itself so as to form a projecting butt, and then flattened to fit in the groove of the needle carrier. The primary member of the butt [that is to say, the member which rises directly from the stem of the needle] receives little or no support from the secondary or reversely bent member, which being free, except at the bend at the outer end of the butt, yields to lateral thrust; hence the greater part of the wear and strain upon the butt are necessarily imposed upon the primary member of the same. Under the usual conditions the chief strain to be resisted by these butts is a shearing strain, resistance to which depends on the dimension of the butt in the direction of the length of the needle, the lateral dimension of the butt being at the maximum the width or gage of the needle, so that it is important to have the butt as broad as possible in this direction. Needle butts formed of a single or unreturned bend are familiar in the art, but such needles have insufficient width of butt in the direction of the length of the needle to resist shearing in a satisfactory manner. It is also important to the function of the needle that the distance between both top and bottom of the butt and the tip of the needle shall be rigidly accurate, but it has heretofore been impracticable to fix this distance by cutting away

or machining to dimension the top and bottom faces of the butt without too much weakening the single wire butt or the unconnected parts of the bent or doubled butt in such needles. The rounded bent end 60 face of the butt as hitherto formed has also necessitated a deeper engagement of the butt with needle-cams than is sometimes desirable.

I have now devised needles overcoming 65 the said difficulties and having also butts of any desired different predetermined relative lengths in respect to the distance between the back of the needle and the highest part of the butt, the end face of the butt being a 70 machined or ground face accurately positioned, which is a matter of importance in connection with machines having devices for differently operating needles of different heights of butt, as will be apparent to those 75 skilled in the art.

In the accompanying drawings, which are upon an exaggerated scale,

Figure 1 is a side elevation of a needle shown as a latch needle illustrating one 80 form of my invention;

Fig. 2 is an enlarged section on the line 2-2 of Fig. 1;

Fig. 3 is an enlarged perspective showing the butt portion of the needle illustrated in 85 Fig. 1;

Fig. 4 is a similar view of a modified form; and

Fig. 5 similarly illustrates another modification.

The shank 1 of a needle formed of flattened wire may be reduced at 2 by swaging or milling as usual, and it may be provided with a hook 3, either rigid as shown or of any desired spring or other form, and may 90 or may not be provided with a swinging latch 4 or a sliding latch. The wire of the shank 1 is bent forward at 5 and turned upon itself at 6 to form a return bend 7, and may, if desired, be provided with a bent tail 95 portion 8 as shown. A flattened bend 5, 6, 7 constitutes the butt of the needle, the portions 5 and 7 being parallel and in contact, or nearly in contact. Throughout the adjacent surfaces in contact or nearly in contact, I unite the portions 5 and 7 by brazing or hard-soldering or by a fusing operation involving additional metal, as illustrated at 9.

The crude butt 5, 6, 7, 9 may now be fin- 110

ished to provide the exact distance between its upper face 10 and its lower face 11 desired to be reached, preferably, as indicated in Figs. 1 and 3, by squaring the wire-edge 5 left by the flattening operation, the needle being held in a jig or templet whereby the distance of these surfaces from each other and the tip 3 is rigidly maintained.

At the same or another operation, the 10 end face 12 of the butt may now be formed as a plane perpendicular to the flattened faces of the needle and parallel with its back edge 13. The distance 12, 13 may thus be made accurate.

15 Although the last mentioned operation removes the greater part of the bend 6, or all of it if desired, the portion 7, 8 of the butt is firmly attached to the portion 5 by the brazed or fused joint, and is a 20 sufficient strengthening addition to the primary member 5 to enable the needle to resist the shearing strains to which it is subject.

As indicated at 14, Fig. 3, the same forming dies and operations, except the operation for forming the face 12, may be relied upon to cut off a needle of a predetermined short length of butt at the plane 14. Needles so formed are more rigidly accurate in the difference of length between long and 30 short butt than those formed by prior methods. The squared end provides a longer bearing on the butt of a longer-butt needle for cams positioned not to contact with a shorter butt, and differentiation of 35 length for different operation may thereby be made less without loss of effect.

As indicated in Fig. 4, it is sometimes possible to make the primary bend 5 and secondary bend 7 with sufficient accuracy 40 of position for certain purposes, and in these cases I may dispense with forming the surfaces 10 and 11, leaving the wire edge 18 of the bend 5, 6, 7, while retaining the same brazing 9 and producing the same 45 surface 12 as above described in the same manner as above indicated.

Copies of this patent may be obtained for five cents each, by addressing the "Commissioner of Patents, Washington, D. C."

As illustrated in said figure, the tail portion 8 may be left off, if desired.

As illustrated in Fig. 5, the primary member 5 may be bent upwardly at 16 to 50 form the secondary member 17, and the said members may then be brazed or fused together as described, the surface 12 [and if desired the surfaces 10 and 11] being formed as before. 55

It will be observed that the superior resiliency and standardization of temper under known heat-treatment of the primary butt member, shank and needle-head which are characteristic of wire needles are retained by my new device in connection with the improved mechanical form of the butt hitherto obtained only by stamping from sheet-metal the entire needle, or by forming the butt-portion of sheet metal and attaching it to a wire-shank in a manner necessarily weakening the needle-shank at the point of attachment. 60

What I claim is:

1. A knitting machine needle having a 70 wire shank and a butt formed by an integral primary bend of the wire shank and a secondary bend thereof fixed together at adjacent edges by a fused metallic joint, the end face of the butt being squared or 75 faced off in a plane substantially parallel to the back of the needle shank.

2. A knitting machine needle having a flattened wire shank and a butt formed of an integral double bend of the shank having primary and secondary members fixed together by a fused metallic joint, the butt being squared or plane-faced on its end and on one or more faces thereof angular to the shank. 85

Signed by me at New York, N. Y., this twenty third day of October, 1916.

ROBERT W. SCOTT.

Witnesses:

WALTER L. TOY,

MARIE C. CURRY.
